UNITED STATES PATENT OFFICE.

WILLIAM H. KASEBERG, OF WASCO, OREGON.

VEHICLE-BRAKE.

SPECIFICATION forming part of Letters Patent No. 437,834, dated October 7, 1890.

Application filed July 23, 1890. Serial No. 359,671. (No model.)

To all whom it may concern:

Be it known that I, WILLIAM H. KASEBERG, a citizen of the United States, residing at Wasco, in the county of Sherman and State of Oregon, have invented certain new and useful Improvements in Vehicle-Brakes; and I do declare the following to be a full, clear, and exact description of the invention, such as will enable others skilled in the art to which it applies to make and use the same, reference being had to the accompanying drawings, and to letters of reference marked thereon, which form a part of this specification.

This invention relates to certain new and useful improvements in vehicle-brakes, and it has more particular reference to that class of brakes in which the brake is applied to the side edges of the felly instead of the face of the periphery of the wheel; and the invention has for its object to provide a simple and powerful wagon-brake of this character, the several parts being so arranged that when a slight pressure is applied to the operating-lever the felly of the wheel will be securely grasped between the brake-shoes and held against rotary movement.

To this end and to such others as the invention may pertain the same consists in the peculiar construction and in the novel combination, arrangement, and adaptation of parts, all as more fully hereinafter described, shown in the accompanying drawings, and then specifically defined in the appended claim.

The invention is clearly illustrated in the accompanying drawings, which, with the letters of reference marked thereon, form a part of this specification, like letters of reference indicating like parts throughout the several views, and in which drawings—

Figure 1 is a perspective view of the running-gear of a wagon, the same being shown as provided with a brake constructed and applied in accordance with my invention. Fig. 2 is a top plan of the brake upon an enlarged scale, the positions assumed by the several parts when the brake is applied being indicated by dotted lines.

Reference now being had to the details of the drawings by letter, A designates the reach, B B the axles, and C C the wheels, of the wagon.

D is a rod or shaft, which is suitably journaled at its inner end within the bearings D' upon the under face of the wagon-bottom in advance of the rear wheel C, the free end of 55 the said shaft being extended outwardly and provided with the operating-lever E at the side of the wagon and conveniently accessible. The crank arm or lever F is at its free end contained within a transverse slot F' in the 60 link G by means of a bolt F², passed therethrough. Within the horizontal slot G², formed in the opposite end of the lever G, are pivotally secured the inner ends of the levers G³, the opposite ends of said levers being pivoted 65 within the rear ends of the levers I, horizontal slots I' being provided in the ends of said levers for their reception.

The levers I are pivoted at a point adjacent to their free ends by means of vertical pivots 70 or bolts I², passed through the timbers J and K, between which timbers the said levers I are passed. The inner faces of the levers I at their free ends are provided with shoes or wearing-plates I³, which shoes, when the brake 75 is applied, are adapted to bear against the outer edges of the felly of the wheel, one upon each side, as shown.

The operation of the brake will be readily understood in connection with the foregoing 80 description. When the brake is off or out of engagement with the wheel, the parts will occupy the positions shown in full lines in Fig. 2 of the drawings. When it is proposed to apply the brake, the lever E is drawn back- 85 ward, thus forcing the levers G³ into the position shown in dotted lines in Fig. 2 of the drawings and forcing the free ends of the levers I inward and applying the brake.

It will be understood that a brake constructed in accordance with my invention may be applied to machines of various kinds, and I do not propose to limit myself in its application to wagons only.

Having thus described my invention, what I 95 claim to be new, and desire to secure by Letters Patent, is—

The herein-described improvement in vehicle-brakes, the same comprising, in combination with the running-gear of a vehicle, the 100 rod D, journaled at its inner end within bearings secured to the lower face of the wagon-

platform and having its free end provided with an operating-lever, the link F, pivotally connected at one of its ends to the shaft D, the levers G⁸, pivotally connecting the levers F and I, the timbers J and K, between which the levers I are pivoted at a point adjacent to their free ends, the levers I, pivoted as described and provided with wearing-plates adapted to engage the side faces of the felly

of the wheel, substantially as shown and described, and for the purpose specified.

In testimony whereof I affix my signature in presence of two witnesses.

WILLIAM H. KASEBERG.
